UNITED STATES PATENT OFFICE.

KURT EVERE, OF CHARLOTTENBURG, GERMANY, ASSIGNOR TO GENERAL ELECTRIC COMPANY, A CORPORATION OF NEW YORK.

INJECTOR FOR OIL-ENGINES.

1,118,407.

Specification of Letters Patent. Patented Nov. 24, 1914.

Application filed September 9, 1914. Serial No. 860,931.

To all whom it may concern:

Be it known that J. Kurt Evers, a subject of the King of Prussia, residing at Charlottenburg, Germany, have invented > certain new and useful Improvements in Injectors for Oil-Engines, of which the following is a specification.

This invention relates to devices for spraying fuel oil into the cylinder of an internal combustion engine, and especially one of the high compression type. In many of the so-called injectors or pulverizers heretofore employed for this purpose, the compressed air impinges on the oil and drives it through the valve opening in direct lines. The oil particles tend to remain intact, except as they may be split up by the expansion of the compressed air. But inasmuch as the most efficient operation requires an extreme subdivision of the fuel and its intimate intermingling with the air in order to form a perfect and quick burning mixture, the injectors or pulverizers above mentioned are not wholly satisfactory.

25 The object of my invention is to provide an injector or pulverizer which will give a good mixture of oil and air, and I accomplish this in the manner hereinafter set forth and particularly pointed out in the 30 claims.

In the accompanying drawings, Figure 1 is a sectional view of an injector or pulverizer embodying my invention; Fig. 2 is a cross-section of the same on the line 2—2; 35 and Figs. 3, 4 and 5 show modifications.

In the wall of the engine cylinder 1, which is provided with the usual water jacket 2, is arranged a receptacle 3 in which is inserted a plug 4, having a longitudinal bore 40 to receive a needle valve 5. The inner end of the receptacle is conical, to form a seat for the conical tip 6 of the valve, which controls the port 7 opening from the receptacle into the cylinder 1. The interior 45 of the plug is cored out to form a central chamber 8 surrounding the valve. A duct 9 communicates with this chamber, and enables a supply of fuel oil to be delivered thereto by a pump or other charge measuring device. The outer portion of the plug fits tightly in the receptacle, but its inner portion is reduced in diameter so as to leave 50 an annular mixing chamber 10 between itself and the wall of the receptacle. Into this chamber compressed air can be admit-

ted through a duct 11 in the plug. A plurality of small holes 12 run through the wall of the plug, connecting the central chamber 8 and the annular chamber 10. There are several rows of these holes and between the 60 rows are circumferential ribs 13 encircling the plug, but not extending to the outer wall of the annular chamber 10, so that said chamber is divided into a tier of small circumferential grooves 14 connected by narrow annular passages 15. These small grooves and passages form a labyrinth through which the air must force the fuel on its way to the port 7.

The operation is as follows: In the device 70 shown in Figs. 1 to 4 inclusive, the oil is assumed to fill the duct 9, the central chamber 8, the mixing chamber 10 and the holes 12 at all times, while a constant pressure of compressed air exists in the duct 11. The 75 fuel pump is timed to deliver a definite quantity of oil to the duct 9 at the instant the needle valve 5 is lifted. The opening of said valve permits the compressed air to blow through the mixing chamber into the 80 engine cylinder, sweeping with it at first the oil which already fills the mixing chamber and after that the oil which is forced by the pump to squirt through the holes 12 into the path of the air blast. The quantity of 85 oil thus driven into the cylinder must equal the amount put in by the pump into the upper end of the central chamber 8. The action of the sudden air blast forces the oil from one annular groove 14 to the next, 90 through the narrow annular passages 15, and the baffling action of the ribs 13 causes the oil to be very finely subdivided and thoroughly mixed with the air by the time it arrives at the port 7, through which the 95 air blast drives it into the engine cylinder.

In order to prevent more than the desired quantity of fuel from being sucked out of the central chamber 8 by the ejector action of the air, and thereby cause unregulated and varying charges entering the cylinder, the holes 12 may be inclined in a direction opposite to that in which the air flows, as shown in Figs. 3 and 4. This arrangement makes it possible to supply to 100 the current of air only that amount of fuel which is delivered by the pump.

When the fuel passes through all of the holes 12 at once, it is desirable to give a smaller cross-section to those which lie far- 110

ther back from the discharge end of the pulverizer, in order that when the load on the engine is light, enough oil may reach the combustion chamber with the first increments of air. Such a construction is shown in Fig. 4, and it is evident that this graduation of the areas of the holes 12 may be adopted when they are radial as in Fig. 1.

When the fuel pump is not arranged to keep the central chamber 8 full of oil all the time, but only to deliver to said chamber separate charges of oil, stroke by stroke, and each charge is swept completely out of the injector at each opening of the needle valve, the construction shown in Fig. 5 is preferred. Here there is a passage 16 from the air duct 11 to the central chamber 8, so that each charge of oil deposited in the injector is exposed to the air pressure in the central chamber 8 as well as in the mixing chamber. The result is that when the needle valve is lifted, the entire quantity of oil in the injector is blown into the cylinder, and a fresh charge of oil is not forced in by the pump until after the needle valve closes. In this case, therefore, the fuel pump is timed to inject the oil alternately with the opening strokes of the needle valve, while in the device shown in Fig. 1 the injection stroke of the pump occurs simultaneously with the opening of the valve.

In accordance with the provisions of the patent statutes, I have described the principle of operation of my invention; together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. A fuel injector comprising a feed valve, an annular chamber concentric therewith, means for supplying fuel and air to said chamber, and a plurality of circumferential ribs in said chamber forming a tier of annular grooves connected by narrow annular passages, the whole constituting a labyrinth or baffle for subdividing and mixing the fuel and air flowing over the edges of said ribs.

2. A fuel injector comprising a receptacle, a plug provided with a central chamber and inserted into said receptacle leaving an annular chamber between them, said plug being also provided with a plurality of holes connecting the two chambers, means for supplying compressed air to said annular chamber, means for supplying fuel to said

central chamber, and means for giving a labyrinthine course to the fuel and air flowing through said annular chamber.

3. A fuel injector comprising a plug containing a central chamber and a plurality of holes through the wall of said chamber, circumferential ribs on the exterior of a portion of said plug between said holes, and a receptacle receiving said plug and leaving an annular chamber around the ribbed portion.

4. A fuel injector comprising a plug containing a central chamber and a plurality of holes through the wall of said chamber, circumferential ribs on the exterior of a portion of said plug between said holes, a receptacle receiving said plug and leaving an annular chamber around the ribbed portion, and a valve for regulating the flow of fuel from said annular chamber.

5. A fuel injector comprising a receptacle, a plug provided with a central chamber and inserted into the receptacle leaving an annular chamber between them, means for supplying compressed air to said annular chamber, and means for supplying fuel to the central chamber, said plug having a plurality of holes connecting said two chambers and inclined in a direction opposite to the flow of air through the annular chamber.

6. A fuel injector comprising a receptacle, a plug provided with a central chamber and inserted into the receptacle leaving an annular chamber between them, means for supplying compressed air to said annular chamber, and means for supplying fuel to the central chamber, said plug having a plurality of holes connecting said two chambers and inclined in a direction opposite to the flow of air through the annular chamber, said holes increasing in cross-section toward the delivery end of the injector.

7. A fuel injector comprising a receptacle, a plug having a central chamber and inserted into the receptacle leaving an annular chamber between them, means for supplying compressed air to said annular chamber, and means for supplying fuel to the central chamber, said plug having a plurality of holes connecting said two chambers and increasing in size from one end of the chambers to the other.

In witness whereof, I have hereunto set my hand this 13th day of August, 1914.

KURT EVERE.
